DESIGN FOR A SPOON

Howard M. Ballou, Charles A. Joslin, and
Laurence W. Wilkin, North Attleboro, Mass.

Application December 26, 1933, Serial No. 50,220

Term of patent 3½ years

To all whom it may concern:

Be it known that we, HOWARD M. BALLOU, CHARLES A. JOSLIN, and LAURENCE W. WILKIN, citizens of the United States, residing at North Attleboro, in the county of Bristol and State of Massachusetts, have invented a new, original, and ornamental Design for a Spoon, of which the following is a specification, reference being had to the accompanying drawing, forming part hereof.

Fig. 1 of the drawing is a plan view of the spoon showing our new design.

Fig. 2 is a cross sectional view on the cross sectional line 2—2 of Fig. 1 for the purpose of illustrating the relief outline of the design of the handle.

We claim:

The ornamental design for a spoon as shown and described.
